UNITED STATES PATENT OFFICE.

THOMAS B. CLARK, OF HONESDALE, PENNSYLVANIA.

DESIGN FOR A CUT-GLASS VESSEL.

SPECIFICATION forming part of Design No. 30,086, dated January 31, 1899.

Application filed December 14, 1898. Serial No. 699,267. Term of patent 3½ years.

To all whom it may concern:

Be it known that I, THOMAS B. CLARK, of Honesdale, in the county of Wayne and State of Pennsylvania, have invented and produced 5 a new and original Design for a Cut-Glass Vessel, of which the following is a full, clear, and exact specification.

Reference is to be had to the accompanying drawings, forming a part of this specification, in which similar characters of reference indicate corresponding parts in both the views.

Figure 1 is an inverted plan view of a cut-glass vessel, showing my design; and Fig. 2 10 is a sectional side elevation of the same.

The leading feature of the design is the lapidary center C—that is to say, a center cut

with faces in imitation of a diamond—and the surrounding ornamentation B.

A minor feature consists in the grouped 20 parts C and B, inclosed by pentagonal figures A, and in the several pentagons grouped around a central quadrilateral figure D, which is ornamented by a rosette E.

Another minor feature is the arrangement 25 of radial fields F, having rosettes G and the ornamental bands H.

I claim—

The design for a cut-glass vessel, as herein shown and described.

THOMAS B. CLARK.
